ROCK-DRILL.

1,080,706.

Specification of Letters Patent.

Patented Dec. 9, 1913.

Application filed January 19, 1909. Serial No. 473,149.

To all whom it may concern:

Be it known that we, EDWIN M. MACKIE and PERCIVAL F. DOYLE, both residing at Franklin, Venango county, Pennsylvania, the former being a citizen of the United States and the latter a citizen of the Dominion of Canada, have invented certain new and useful Improvements in Rock-Drills, of which the following is a specification.

10 Our invention relates to rock drills, more particularly those of the type known as hammer drills, and the object thereof is to provide a drill with an air feed device having a novel and reliable construction of 15 governor capable of regulating the degree of pressure admitted to the air feed device so that any predetermined amount or any amount less than the working pressure of the drill may be employed for such de- 20 vice and also to provide a governor of this character with means for releasing the pressure or motive fluid so admitted.

Other novel and advantageous features of construction and operation will be ap- 25 parent from the description hereinafter given.

In the drawings, Figure 1 is a plan view of our improved rock drill with an air feed device attached thereto; Fig. 2 a side view 30 of the rock drill or machine showing the rock drill proper in section and the air feed device partly in section; Figs. 3, 4, 5 and 6 are sections on the lines 3—3, 4—4, 5—5 and 6—6 respectively of Fig. 2, but on a 35 somewhat larger scale; Fig. 7 a section on the line 6—6 of Fig. 2; Fig. 8 a section on the line 8—8 of Fig. 9; and Fig. 9 a section on the line 9—9 of Fig. 1 or a section on line 9—9 of Fig. 8.

40 Referring to the present embodiment of our invention, the elements of the hammer are of the usual construction, so that it will suffice to refer to same in general terms.

As shown in Fig. 2, the hammer piston 1 re- 45 ciprocates in the cylinder 2 to which the fluid pressure is admitted and released by means of the valve 3 working in coöperation with the piston 1, with the result that the piston will be reciprocated in opposite 50 directions and caused to deliver its blow on its forward stroke. The valve is adapted to operate in a suitable valve box or bushing 4, whose front end is closed from the cylinder or piston chamber by means of the valve

box cap 5. The cylinder is provided with a 55 back head 6 having its forward end formed as a socket whose upper or inner end 7 is adapted to contain the valve box 4 and whose lower or outer end 8 is adapted to receive the rearward end 9 of the cylinder. 60 This end of the cylinder, as well as the inner diameter of the outer end of the back head socket, are suitably machined so as to slip freely upon each other, the length of fit being sufficiently long to preserve alignment of cylinder 2 and the head 6 so that the end surface 10 of the socket will come "true" with the end surface 11 of the valve box. This fitting of the back head and cylinder provides a slip joint and the parts 65 are clamped together by the same clamping means which clamp the front head to the cylinder as hereinafter described.

The back head 6 is provided with a rearward extension 12 in which is adapted to 70 fit the forward end of the hollow feed piston 13 of the air feed device. The extension 12 is slotted at its upper end as indicated in Figs. 1 and 2, in order to act as a clamp in connection with the clamping 75 bolt 14, whereby upon tightening such bolt the described parts which thus have a slip joint connection are secured together. As indicated in detail in Fig. 5, the clamping bolt 14 is so positioned that it lies in a 80 groove formed on one side of the feed piston 13, with the result that such piston is 85 locked in place and prevented from rotating.

Describing the air feed device, the same 90 comprises the feed barrel 15 and the center piece 16 which closes the upper end of such barrel. The hollow feed piston 13 is provided with fluid pressure connections and in the present instance with a fluid pressure 95 governor or regulator for such pressure now to be described.

The back head 6 is provided with a fluid 100 pressure passage 17 which supplies the fluid pressure to the operating parts of the drill when the throttle valve is opened. This throttle valve consists in the present instance of a three-way valve 18 of the plug type, with a central passage 19 communicating with a suitable source of fluid pressure supply, as indicated in Fig. 1. The valve is provided with an operating handle 20 which when moved in an anti-clockwise direction,

Fig. 2, turns the valve in position to preliminarily admit the fluid pressure to the air feed device and then to the drill. Upon the first movement of the valve an elongated passage 21 will be brought into communication with a port and passage 22 which is connected by means of the pipe connection 23 with the fluid pressure governor indicated generally by 24. This governor or pressure regulator consists of a casing 25 having a piston chamber in which reciprocates a piston 26 having a central passage 27 and radial passages 28. This piston is held in normal position with a yielding pressure which, in the present instance, consists of a spring 29 exerting its influence upwardly against the piston 26 through the medium of the sleeve 30 movable as a piston in the lower and enlarged diameter of the casing 25. The tension of this spring is adjustable by hand by means of the adjusting nut 31 which, when screwed in one direction or the other regulates the tension of such spring. When the fluid pressure is admitted to the governor as hereinbefore described it will tend to force the piston 26 downwardly and if such pressure exceeds the force of the spring, such piston will be moved downwardly with the result that the fluid pressure will be admitted through the passages 27 and 28 to the cross passages 32 and 33 and into the longitudinal chamber 34 in the interior of the feed piston 13. The fluid pressure now filling this chamber 34 will act upon the surface 35 of the rearward end of the feed barrel 15 and will force the feed piston away from such end until the drill steel is brought up against the material to be drilled.

It is desirable to regulate the degree of pressure admitted to the air feed device and particularly to maintain the same at any desired pressure less than the working pressure, that is the fluid pressure operating the drill. This is an important feature, inasmuch as it has been found in practice that for the efficient working of the drill the same should be held or forced more firmly against the formation being drilled when it is hard, like granite, than against a soft formation like sandstone. In practice, in order to obtain the desired pressure in the chamber 34 of the air feed device, the adjusting screw or cap 31 being screwed inwardly to its full extent to give the spring 29 its maximum tension, the valve 18 is operated to admit air to the governor and thereupon the adjusting screw 31 is slowly unscrewed or backed off, thereby lessening the resistance of the spring 29 until the fluid pressure in the chamber 34 is at the required degree, which will be less than the pressure of the fluid entering the governor to an amount equal to the resistance of the spring 29.

After the air feed pressure has been estab-

lished, a continued turning of the handle 20 of the three-way valve will bring the port 35 therein into communication with the supply passage 17 in the upper head 6 and the drill will be set into operation.

For the purpose of exhausting the pressure from the governor when the valve is in the normal position shown in Fig. 2, we provide the plug valve with a special port 19* which communicates with the atmosphere and is also arranged to communicate when in said normal position with a passage 18* in the body of the valve, which latter passage communicates with the supply passage 22 hereinbefore described. When the governor is thus released of pressure the spring 29 will return the parts, including the piston 26, to normal position, as shown in Fig. 7, whereupon the pressure from the chamber 34 will escape through passages 32 and 33, thence through passage 26* and port 26*, as indicated by the arrows in Fig. 7.

When the drill is to be used without the air feed device the clamping bolt 14 is removed and the feed piston is withdrawn from the extension 12 of the back head and the air feed device is replaced by another piece suitable for the work to be done. Also the pipe connection 23 is disconnected from the valve and a suitable plug inserted in the opening 22.

The front head of the drill is adapted to be secured to the cylinder by a slip joint in the same general manner as the back head and to this end such a front head 36 is suitably machined on its upper end to form a cap for the lower end of the drill cylinder. This head, as well as the back head, is rigidly held in position by means of the tie rods or bolts 37 which serve to clamp such heads to each other and to the interposed cylinder. The interior of the upper end of the lower or front head is provided with a two diameter bore in order to receive the striking piece 37' which is of corresponding two diameters. This striking piece is arranged to receive the blow of the hammering piston 1 and to transmit the same to the inner end of the drill steel 38 which is inserted in the front end of the front bushing 36 and received by the chuck bushing 39. In order to facilitate the removal of the chuck bushing the front head is slotted, as seen in Figs. 1 and 2 and provided with a clamping bolt 49 for clamping such head upon the bushing. This clamping bolt is adapted to lie in a depression formed on one side of the bushing, so as to prevent the latter from rotating. This front head forms a water head and to this end the same is provided with a water supply passage 41 arranged to communicate with a water supply passage 42 extending longitudinally of the drill cylinder, the same being connected to any suitable source of water or both air

and water controlled by suitable valve mechanism 43. In order to provide for a proper connection between the passages 41 and 42 and also to locate or determine the proper 5 relative position of the front head and the cylinder, we provide a hollow dowel 44 located at the joint between the front head and cylinder. The water passage 41 communicates with the bore of the front head 10 at the shoulder formed between the two diameters of the bore and the water so admitted is adapted to flow through radial passages 45 in the striking piece 37', which passages communicate with a common central passage 46. This passage in turn is 15 arranged to communicate with a central passage 47 in the drill steel. In order to prevent leakage of the fluid around the striking piece the same is provided with 20 suitable packing 48, preferably leather, and likewise for the same purpose the drill steel is provided with suitable packing 49 arranged behind the chuck bushing 39 and around the inner end of the drill steel. Under 25 this construction and arrangement the water or air and water mixed may be admitted through the passages 42 and 41, thence through the passages 45 and 46 in the striking piece, and finally through the 30 passage 47 in the drill steel to the cutting end of the latter, thereby obtaining in a novel and simple manner all of the advantages recited in the preamble of this specification. By the provision of the governor 35 for the air feed device a predetermined degree of pressure may be provided for such device and maintained thereat according to the strength or firmness of the formation being operated upon. Furthermore, by reason 40 of the so-called slip joint connections we are enabled to eliminate threaded connections between the heads and the cylinder and also between the air feed and the cylinder, which threaded connections are very undesirable 45 and a source of considerable trouble on account of the threads becoming dry and rusty and making it difficult to unscrew one member from the other after the drill has been in service even for a short time.

50 We claim:

1. In combination with a rock drill, an air feed device coöperating therewith, a valve for admitting pressure fluid to the air feed, and a fluid pressure actuated governor for controlling the degree of pressure admitted to such device, said governor having provision for releasing such pressure therefrom.

2. In combination with a rock drill, an air feed device coöperating therewith, a valve for admitting pressure fluid to the drill and to the air feed device, and a fluid pressure actuated governor interposed between such valve and said device for controlling the degree of pressure admitted to

such device, said governor having provision for releasing such pressure therefrom.

3. In a rock drill, the combination with a motive fluid operated motor and motive fluid operated feeding means therefor, of means for delivering motive fluid under pressure to the motor and to the feeding means, and mechanism for varying the pressure of the motive fluid delivered to the feeding means relative to that delivered to the motor, said mechanism having provision for releasing such motive fluid therefrom.

4. In a rock drill, the combination with a motive fluid operated motor and motive fluid operated feeding means therefor, of means for delivering motive fluid under pressure to the motor and to the feeding means, and mechanism for varying the pressure of the motive fluid delivered to the feeding means without affecting the pressure of the fluid delivered to the motor, said mechanism having provision for releasing the motive fluid delivered to the feeding means.

5. In a rock drill, the combination with a motive fluid operated motor, and motive fluid operated feeding means therefor, of a supply conduit having branches leading respectively to the motor and to the feeding means, and variable pressure reducing means located in the branch that leads to the feeding means, said means having provision for releasing the motive fluid delivered to the feeding means.

6. In a rock drill, the combination with a motive fluid operated motor, of motive fluid operated feeding means therefor, means for delivering motive fluid to the motor and feeding means, including separate channels leading thereto, and variable pressure-reducing mechanism controlling the passage of motive fluid through one of said channels, said mechanism having provision for releasing the motive fluid delivered to the feeding means.

7. In combination with a rock drill, an air feed device coöperating therewith, a valve for supplying the pressure fluid admitted to the air feed device, and a fluid pressure actuated governor interposed between such valve and said device for admitting the pressure fluid to the latter and its release therefrom, such governor comprising a casing with ports communicating respectively with the feed device, with the atmosphere and with the supply from said valve, a piston controlling the first two mentioned ports, and means operating upon the piston to cause it to resist the pressure fluid admitted to the governor by the valve.

8. In combination with a rock drill, an air feed device coöperating therewith, a valve for supplying the pressure fluid admitted to the air feed device, and a fluid pressure actuated governor interposed be-

5 between such valve and said device for admitting the pressure fluid to the latter and its release therefrom, such governor comprising a casing with ports communicating respectively with the feed device, with the atmosphere and with the supply from said valve, a piston controlling the first two mentioned ports, a sleeve movable in said casing and adapted to bear against the piston, and
 10 a spring coöperating with said sleeve.

9. In combination with a rock drill, an air feed device coöperating therewith, a valve for supplying the pressure fluid admitted to the air feed device, and a fluid pressure actuated governor interposed between such valve and said device for admitting the pressure fluid to the latter and its release therefrom, such governor comprising a casing with ports communicating respectively with the feed device, with the atmosphere and with the supply from said valve, a piston controlling the first two mentioned ports, a sleeve movable in said casing and adapted to bear against the piston, an adjustable screw plug screwing into said casing, and a spring interposed between the sleeve and the plug.

10. In combination with a rock drill, an air feed device coöperating therewith, a valve for supplying the pressure fluid admitted to the air feed device, and a fluid pressure actuated governor interposed between such valve and said device for admitting the pressure fluid to the latter and its release therefrom, such governor comprising a casing with communication respectively with the valve, feed device and atmosphere, a piston movable within the casing and having ports adapted to register with the feed device communication, said piston being arranged to govern the communication to atmosphere and the casing having a passage adapted to communicate between the feed device and the communication with atmosphere when not closed by the piston.

11. In combination with a rock drill, an air feed device coöperating therewith, a valve for admitting pressure fluid to the air feed device, and a fluid pressure actuated governor interposed between such valve and said device for controlling the degree of pressure admitted to such device, said valve having means for releasing the pressure admitted to the governor and acting upon the latter.

12. In combination with a rock drill, an air feed device coöperating therewith, a valve for admitting pressure fluid to the air feed device, and a fluid pressure actuated governor interposed between such valve and said device for controlling the degree of pressure admitted to such device, said valve

being adapted to release the pressure admitted to the governor, and having a way connecting between the governor and a source of motive fluid supply for the admission of motive fluid to the governor and having a second way connecting between the governor and the atmosphere when the first mentioned way is closed for releasing the motive fluid acting upon the governor.

13. In combination with a rock drill, an air feed device coöperating therewith, a valve for supplying the pressure fluid admitted to the air feed device, a fluid pressure actuated governor interposed between such valve and said device for admitting the pressure fluid to the latter and its release therefrom, such governor including a casing having ports and passages communicating respectively with the valve, feed device and atmosphere, and a piston movable in the casing for governing said ports and passages, said piston being normally in a position of release but capable of positions of admission and of lap, said valve having means for releasing the pressure upon the piston to permit the latter to return to normal position.

14. In combination with a rock drill, an air feed device coöperating therewith, a valve for supplying the pressure fluid admitted to the air feed device, a fluid pressure actuated governor interposed between such valve and said device for admitting the pressure fluid to the latter and its release therefrom, such governor including a casing having ports and passages communicating respectively with the valve, feed device and atmosphere, and a piston movable in the casing for governing said ports and passages, said piston being normally held in a position of release by an adjustable spring pressure but capable of positions of admission and of lap, said valve having means for releasing the pressure upon the piston to permit the latter to return to normal position.

15. In combination with a rock drill, an air feed device coöperating therewith, a valve for admitting pressure fluid both to the drill and to the air feed device, and a fluid pressure actuated governor interposed between such valve and said device for controlling the degree of pressure admitted to such device, said valve having means for releasing the pressure admitted to the governor and acting upon the latter.
